UNITED STATES PATENT OFFICE.

THOMAS H. SLY, OF DUNMORE, PENNSYLVANIA.

GRATE-BAR.

1,114,195.

Specification of Letters Patent.

Patented Oct. 20, 1914.

Application filed December 22, 1913. Serial No. 808,193.

To all whom it may concern:

Be it known that I, THOMAS H. SLY, a citizen of the United States, residing at Dunmore, county of Lackawanna, and State 5 of Pennsylvania, have invented certain new and useful Improvements in Grate-Bars, of which the following is a specification.

This invention relates to grate bars. The proper burning of fine fuel under a steam boiler, requires a forced draft furnished by a fan, turbine or steam jet blower, which introduces the air into the ash pit at a high pressure and the distribution of the air through the grate bars into the fuel in order 10 to keep the fine fuel in a state of uniform combustion and to permit the evolved gases to burn. The fewer "dead spots" where the forced draft does not strike the fuel, the better will be the combustion and the greater 15 the quantity of the heat units. Grate bars have also been subject to warping and burning out, despite the provision of the trussing ribs commonly used in connection therewith. It has heretofore been proposed to provide 20 grate bars with supplemental or secondary perforated tops which directly support the burning fuel, to the end that warping and burning out of the main grate bar may be minimized and the distribution of air to the 25 fuel increased. So far as I am aware, however, such prior constructions have been subject to various defects, among which may be mentioned that the connections or manner of support of the supplemental grate 30 bars have resulted in distortion and fusing onto the main grate bar, rendering it difficult and sometimes impossible to remove the supplemental sections when they are burned out or warped and require substitution of others. Another defect which has 35 been incident to earlier constructions has been the imperfect distribution of the air to the fuel, many "dead spots" resulting with consequent loss of heat and imperfect combustion.

My invention relates to that general type of grate bar designed for the burning of fine fuel under forced draft and composed of a main grate bar having openings for the 40 passage of the air under pressure and supplemental removable sections which are perforated for the admission of the air direct to the fuel.

In a grate bar of the foregoing general 45 type, my object is to provide improved supplemental detachable sections mounted upon,

connected to, and combined with the main grate bar in a novel manner, whereby they may be readily assembled or disconnected therefrom; second, to provide the supplemental grate bar sections with several air supplying openings and an improved arrangement of air distributing grooves or channels and arranged and combined with the main grate bar so that the air openings 60 are always subject to air supply and whereby the air is delivered into the bed of the fuel supported by said sections in such manner that practically no "dead spots" exist in the fuel and a more perfect combustion is 65 effected than has heretofore been possible.

The invention consists of a grate bar having constituent parts and features as also novel combinations of elements, one embodiment of which is set forth fully hereinafter, but which is to be considered as 70 illustrative, rather than restrictive, of the scope of the invention.

In the accompanying drawings: Figure 1 is a plan view; Fig. 2, a side elevation, 80 partly in section; Fig. 3, a bottom view of the main grate bar; Fig. 4, an end elevation; Fig. 5, a detail plan of one of the detachable grate bar sections; Fig. 6, a similar view, broken away, of a modified grate 85 bar section; Fig. 7, a section on line 7—7, Fig. 5; Fig. 8, a section on line 8—8, Fig. 6; and Fig. 9, a section on line 9—9, Fig. 6.

The main grate bar 1 is provided with the usual trussing ribs 2 and it has throughout its top, between said ribs, numerous air holes or perforations 3 which contract upwardly and open out of the upper face of the grate bar, such contraction resulting in increasing the pressure of the air forced 90 through these openings. In addition to the openings located between the ribs 2, the longitudinal edges of the grate bar have semi-openings 4 which, together with corresponding openings on the next adjacent 95 grate bar, provide complete openings of substantially the size and form of the openings 3. The resulting construction is that the only part of the grate bar through which the forced draft does not pass is the 100 relatively small, narrow area representing the thickness of the ribs 2. With this construction, I obtain a greater flow of air than has been possible with those grate bars 105 which have elongated slots only and no feature similar to the semi-apertures 4. At intervals of the longitudinal median line or

110

axis of the grate bar, there are bolt holes 5 for the passage of the bolts 6 which connect the detachable supplemental grate bar sections 7 to the main grate bar 1, in superposed relation thereto.

The sections 7 are of square form, having extending through their centers countersunk bolt holes 8 to receive the bolts 6. The heads of the bolts rest in the countersunk bolt holes and the lower ends of the bolts are provided with nuts 9 which may be separately removed to permit separate detachment of any of the supplemental sections 7 without interfering with the remaining sections, as for instance, when one of said sections 7 is worn out or broken and another has to be substituted therefor. I do not limit myself to sections 7 of square form, but they are preferably of polygonal form having straight sides which may be arranged in contact with each other at the upper edges 10 and, preferably, the sides of the sections 7 are downwardly sloped or beveled to minimize the contacting part at 10 and to prevent fusing as well as to provide for expansion and contraction.

The sections 7 have legs 11 cast integral therewith, said legs resting upon the top of the grate bar 1 and against lugs 12 formed on said grate bar 1, the said lugs preventing lateral displacement of the sections 7. The provision of the legs and the lugs causes a centering or securement of the sections 7 in such fashion that but a single bolt 6, located at the center of the section, is necessary to properly secure the section to the grate bar 1, and consequently, but one bolt has to be unfastened to permit removal of a given section or applied to permit securement of a section to the grate bar.

The legs 11 support the sections 7 above the top of the grate bar 1 and there is consequently, a free air space 13 between the main grate bar 1 and the supplemental grate bar formed of the sections 7 which permits a free distribution of the air to the openings or holes 14 in the section 7. The fuel being supported by the sections 7, instead of directly on the grate bar 1, the latter is kept cool by the air beneath it and that in the space 13 and there is little tendency to warp or burn out.

The openings or perforations 14 taper upwardly like the openings or perforations 3 to choke down the air passing from space 13 into said perforations 14 and to thereby increase the pressure. The upper ends of the openings or holes 14 are flared, as shown at 15, which more readily distributes the air. The upper face of each section 7 is provided with distributing grooves or channels 16 which are wider at the top than at the bottom to effect a thorough distribution 65 of the air to the fine fuel lying on the sec-

tions 7. The flared parts 15 and the grooves or channels 16 may assume different forms, and I do not limit myself, except where specified in the claims, to the design or form shown in the drawings.

One modification is shown in Figs. 6, 8 and 9, where in substitution for the holes 14, I provide elongated slots 17 which are provided with elongated flared mouths 18 for the same purpose as the mouths 15. The face of the sections 7 is in this form, provided with grooves or channels 19 wider at the top than at the bottom, and connecting the flared mouths 18 of the different openings or slots 17.

My invention in respect to the channeling of the upper faces of the sections 7 resides, not in the detailed construction herein set forth and shown in the drawings, but in the provision of channels, however formed, 85 communicating with the openings, however formed, which extend from the bottom to the top of the sections 7 and, further, in such construction combined with the flared mouths of the openings which extend 90 through the sections 7, whether such flared mouths be of the form shown at 15, at 18, or of other form.

The air under pressure passing through the opening 14, or 17, spreads out over practically the entire upper face of the section and is distributed with great uniformity to the fine fuel resting on the sections 7, thus insuring a high degree of combustion and minimizing "dead spots" in the fuel.

The supplemental grate bar being composed of individual sections 7, and thus split up into a plurality of parts, has little tendency to warp because these sections have no ribs, are of equal thickness, and the air distribution is substantially equal over the entire supplemental grate bar thus provided.

Having thus described my invention, what I claim as new and desire to secure by Letters Patent, is:—

1. A grate bar composed of a main part having openings, and a supplemental part surmounting the main part and separated therefrom by a free air space, said supplemental part being composed of independently attachable and removable sections each of which has air openings extending therethrough and which is provided on its upper surface with channels extending lengthwise and crosswise thereof and arranged and adapted to distribute the air throughout and over substantially the entire fuel supporting surface thereof.

2. A grate bar consisting of a main bar having air openings extending therethrough and a supplemental fuel supporting bar composed of a plurality of independent, independently removable sections surmounting and independently detachably connected to the main bar and separated therefrom by an

intermediate air space, said sections being each provided with several air distributing openings extending from their lower to their upper faces and communicating with said air space and also having on their upper fuel supporting faces air distributing channels extending in different directions lengthwise and crosswise thereof from the different air distributing openings aforesaid.

10 3. A grate bar composed of a main part having numerous relatively small openings, and a supplemental part surmounting the main part and whose top is raised above and separated from the top of the main part by a free air space, said supplemental part being composed of independently attachable and removable sections each of which has air openings extending therethrough and is provided on its fuel supporting surface with intersecting air distributing channels arranged lengthwise and crosswise of the bar and communication with said openings.

4. A grate bar consisting of a main grate bar and a supplemental grate bar composed of a plurality of sections each having legs resting on the main grate bar and supporting and spacing it above the main grate bar, and independent connectors fastening the said sections to the main grate bar. 25

5. A grate bar consisting of a main grate bar and a supplemental grate bar composed of a plurality of sections each having legs resting on the main grate bar and supporting and spacing it above the main grate bar, 30 said main grate bar having lugs engaging the legs of the said sections, and independent connectors fastening said sections independently to the main grate bar. 35

In testimony whereof, I hereunto affix my 40 signature in presence of two witnesses.

THOMAS H. SLY.
